William C. Coleman
BY *Attwater Brown*
ATTORNEY

UNITED STATES PATENT OFFICE.

WILLIAM C. COLEMAN, OF WICHITA, KANSAS.

CENTRIFUGAL MACHINE.

Application filed May 28, 1923. Serial No. 641,968.

To all whom it may concern:

Be it known that I, WILLIAM C. COLEMAN, a citizen of the United States, residing at Wichita, in the county of Sedgwick and State 5 of Kansas, have invented certain new and useful Improvements in Centrifugal Machines; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 This invention relates to centrifugal machines and particularly to centrifugal separators or amalgamators for separating metal from ore.

20 The invention is primarily intended for use in separating metals from ore pulp or sludge. The ore sludge is passed through the machine and during the passage therethrough, a body of mercury absorbs the metal, allowing the earth to pass out through 25 the machine. After the mercury has become saturated with the metal, the metal is recovered in any appropriate manner.

30 The invention consists in certain novel details of construction and combinations of parts, all of which will be hereinafter described, reference being had to the accompanying drawings, in which—

35 Fig. 1 is a vertical, longitudinal, sectional view through a separator constructed in accordance with my invention.

Fig. 2 is a perspective view of a distributor, and

40 Fig. 3 is a perspective view of the bottom part of the casing with the cover plate removed, part of the bottom part or member being broken away to show the interior thereof.

45 In carrying out the invention I provide an outer casing consisting of a hollow cup-shaped member 1 and a cover 2 which constitutes a rotor driven by an appropriate means as, for example, by the hollow shaft 3. The bottom member of the cover or outer rotor consists of a cup-shaped member having 50 a bottom 4, at the center of which is an opening 5 surrounded by an inwardly extending, upstanding collar 6 having radial impeller blades 7 at its periphery. The upper end of the member 1 is provided with 55 an exterior flange 8 having an offset portion

9 to form a shoulder to receive a packing ring 10 extending inwardly beyond the inner wall of the member 1. Resting upon the offset portion and the ring 10 is a washer or gasket 11 upon which rests the flange 12 of the cover 2, the flanges 8 and 12 being secured together by suitable fastening devices, as bolts 13.

60 Within the casing formed by the members 1 and 2 is a distributor comprising a disk 14 having a depending flange 15, between the ends of which is a ring-shaped spreader or distributor flange 16. The distributor is spaced from the collar 6. The flange 15 is of a diameter sufficient to overlap the 70 impeller blades 7 but also of such diameter that it is spaced inwardly from the walls of the member 1. At the top of the distributor is a collar 17 fastened to the disk 14 by a spider 18 so that spaces 19 will 75 be provided to permit the material to pass into the separator from the hollow shaft 20 fastened to the collar 17.

80 The hollow shaft 20 is concentric with the shaft 3, being within it but in spaced relation thereto.

85 The member 1 carries a body of mercury 21 which assumes the position shown in Fig. 1 when the casing is rotated. The outer rotor consisting of the members 1 and 2 is rotated at a speed sufficient to cause the body of mercury 21 to assume the position 90 shown in Fig. 1 and the material is fed through the hollow shaft 20 and passes through the openings 19 over the distributor 95 consisting of the disk 14, flange 15 and flange 16 so that it is flowed over the mercury band 21. The distributor can be driven in the same direction as the casing or outer rotor, preferably at a lower speed, or in a reverse direction, the purpose being to cause the incoming metal containing ore pulp or sludge to pass over the body of mercury which has an affinity for the metal so that the metal is separated from the earth, the 100 earth or tailings passing to the bottom of the casing where they are picked up by the impeller blades 7.

105 It is intended that the metal be entirely separated from the earth by a single operation but where that is impossible, I may arrange a plurality of separators in series and in that event, all of the distributors can be secured together and driven from the hollow shaft 20. If two distributors 110

are employed, for example, the next succeeding one can have a rod with a threaded end to be received in a threaded socket 22 on the disk 14, as will be clearly seen by reference 5 to Fig. 1.

When the material flows through the openings 19, it will pass over the disk 15 and over the flange 16, where it will be directed against the surface of the circular column 10 of mercury and, obviously, the material not absorbed by the mercury will gravitate to the bottom of the casing member 1, where, upon the proper accumulation, it will be discharged through the opening 5 due to 15 the pressure of the incoming pulp.

The device can be readily assembled and disassembled, the parts can be inexpensively constructed and obviously, the material treated will be subjected to a sort of scrubbing 20 action by the mercury ring so that the metal will be efficiently removed from the earth, pulp or sludge.

What I claim and desire to secure by Letters-Patent is:

- 25 1. A separator comprising an inner rotor and an outer rotor, the outer rotor comprising a casing having a mercury-receiving space, the inner rotor comprising a disk having a depending flange, and a distributing flange on the depending flange, the periphery of the distributing flange being within the mercury space.
- 30 2. A separator comprising an inner rotor and an outer rotor, the outer rotor comprising a casing having a mercury-receiving space, the inner rotor comprising a disk having a depending flange, a distributing flange on the depending flange, the periphery of the distributing flange being within the mercury space, and means for discharging material from the bottom of the casing.
- 35 3. A separator comprising an inner rotor and an outer rotor, the outer rotor comprising a casing having a mercury-receiving

space, the inner rotor comprising a disk having a depending flange, a distributing flange on the depending flange, the periphery of the distributing flange being within the mercury space, and means for discharging material from the bottom of the casing, said 45 means comprising a collar surrounding an opening in the bottom of the casing and 50 provided with radial impeller blades.

4. A centrifugal separator, comprising an inner member and an outer member, means 55 for effecting relative movement between the members, the inner member having a disk-shaped flat top, a hollow shaft for delivering material upon the flat top, a depending cylindrical flange on the periphery of the disk-shaped top, and a spider connecting the hollow shaft with the inner member, the spider spacing the lower end 60 of the hollow shaft from the disk-shaped top, the outer member having a bottom wall 65 with a raised central portion, and a collar in the bottom of the outer member surrounding an outlet opening and projecting upwardly into the space surrounded by the flange.

5. A centrifugal machine comprising an inner rotor and an outer rotor, the outer rotor consisting of a hollow member having a central opening at its bottom, a collar surrounding the central opening having radial impeller blades, a flange at the upper 70 end of the outer rotor having an offset portion, a packing ring in the offset portion, a cover connected to the flange, a gasket between the cover and the flange, the inner 75 rotor consisting of a disk, a collar, spaced members connecting the collar to the disk, a depending flange on the disk, and a ring-shaped flange intermediate the ends of the depending flange.

In testimony whereof I affix my signature.

WILLIAM C. COLEMAN.
